FEED REGULATING DEVICE

Georg Spiess, Leipzig, Germany

Application June 2, 1934, Serial No. 728,756
In Germany June 3, 1933

7 Claims. (Cl. 271—38)

This invention relates to a device for regulating the feed of an adjusted pile to the sheet separating means, in which the foremost sheet of the pile, by closing a control nozzle or striking a 5 feeler, automatically starts or stops the ratchet gear effecting the feed of the pile, particularly for sheet separation by means of a suction roller, suction wheels, or the like.

The known suction nozzle control according 10 to which the pile of sheets closes a suction nozzle disposed in its support suffers from the drawback that the separation of the sheets is interfered with by the adhesion of the sheets to their support. Mere feeler control is likewise unsatisfactory for the reason that it is quite a bothersome task to return the control device to operating 15 position. These defects become particularly manifest when the sheets are separated by a suction roller or suction wheels, and one directly 20 after the other, and then transported, a method which is otherwise advantageous per se.

To overcome these troubles the invention provides that a feeler projecting from below into the conveying path of the pile and held in control 25 position is moved by the contact of the sheet with a control suction nozzle forming part of the regulating device in such a way that, owing to the suction pressure of the suction nozzle, it will close the suction conduit thereof and a 30 piston provided in the suction conduit and connected with a ratchet pawl will carry out a motion which in known manner serves only for temporarily stopping the ratchet gear of the pile during the working stroke concerned. Furthermore, an air control member disposed in 35 the suction conduit is so controlled that it will temporarily connect the suction conduit with the outer air at each operation of the ratchet gear and thus bring about the disengagement of the 40 feeler from the suction nozzle. In this way, highly sensitive regulation of the feed is insured and can be applied to both rhythmic and continuous sheet separation without any rhythm. In the latter case, it is only necessary temporarily to 45 interrupt the connection between the nozzle and the suction pump at each cycle of operation of the ratchet gear causing the transport of the pile of sheets so as to allow the feeler to swing back when the series of sheets has to be fed forwardly 50 owing to the removal of the end or top sheet. The suction nozzle can be attached at a suitable point located so that it will be closed by the motion of the feeler taking place when the end sheet contacts with the feeler.

55 The invention further provides for regulating

the position of the feeler spring relative to the support of the pile of sheets, i. e., the distance for which the spring exceeds the support, in dependence upon the distance between the suction roller or wheels and the support for the pile of sheets. 5

By way of example, one form of the invention is illustrated in the accompanying drawing, in which all parts not necessary for understanding the invention are omitted and in which

Fig. 1 is a side elevation, partly diagrammatic of one embodiment of this invention.

Fig. 2 is a detail side elevation, partly diagrammatic, of certain parts of a modified form of this invention.

Referring to the drawing, the single revolution 15 shaft 2 disposed in the feeder frame 1 carries a crank disc 3 which by means of the rod 4 causes oscillation of the feed arm 5 forming part of a ratchet gear and being loosely arranged on the shaft 6. The arm 5 carries at its end 20 a pawl 8 disposed on a bolt 7, and on the bolt 7 there is also mounted a roll 10, which is rotatable on the bolt 9. The pawl 8 is drawn by the spring 11 against the teeth of a ratchet wheel 12 keyed to the shaft 6 in the frame 1. The rotary 25 motions of the ratchet wheel 12 caused by the pawl 8 are transmitted by a bevel gear 13 secured to the shaft 6, another bevel gear 14, a shaft 15 and additional gears, not shown, to a pile transport roller, not shown, of a round pile. The 30 adjusted sheet pile 16 is advanced on the table 17 having an extension plate 18 in known manner by the conveyor belts 19 passing over an idler roll 20. By this means the topmost sheet 35 is moved into a position suitable for the separation of the sheet from the pile. For separating the sheet from the pile the suction wheels 21, which may be replaced by a suction roller, are arranged on the shaft 22 disposed in the arms 24 secured to a shaft 23 which carries also a stop 40 arm 25 drawn by the spring 26 against a set screw 27 attached to the frame 1. By adjusting the set screw 27 the distance of the suction wheels from the surface of the pile can thus be 45 regulated. The suction wheels 21 are driven from the shaft 2 by means of the gear wheels 28, 29, 30, 31 and 32.

The device for automatically regulating the pile feed and interrupting it when the point of the adjusted pile has attained the position required for sheet separation comprises a feeler spring 33 whose free upper end extends between the front end of the extension plate 18 of the table 17 and a sheet conveying or tape roller 34 transporting the separated sheets in known man- 55

ner over the feed table 35. The free upper end lies in the path of the sheets, so that it will be struck by the upper sheet of the pile in the course of conveyance and pressed back thereby. The 5 lower end of the feeler spring 33 is secured at 36 to a tube 37 attached by a stub shaft 54 to the frame 1 and connected by a conduit 38 with the suction side of an air pump (not shown). At its upper end, the tube 37 is provided with a suction 10 nozzle 39 opening towards the back of the feeler spring 33 and being closed by the latter when it is pressed back by the point of the pile. To insure reliable closing the nozzle is preferably fitted with a rubber disc 40 or the like. From the 15 tube 37 extends a branch 41 to a cylinder 42 in which a piston 43 is displaceably disposed against the pressure of a spring 44. The piston rod 45 acts with its free end on a pawl 47 which is swingingly disposed by means of a fixed bolt 46 and 20 controlled by a return spring 48. The tooth of the pawl 47 faces the ratchet toothing of a segment 49 screwed to one end of a cam plate sector 50 rotatably positioned on the shaft 6 between the ratchet wheel 12 and the frame wall 1. Responding 25 to the tension of a spring 51, the sector 50 abuts with its circumferential stop nose 52 against an extension of the bolt 7 serving as stop and cooperates in the motion of the feed arm 5 of the ratchet gear. At the other end of the cam 30 plate sector 50 a cam surface 53 is provided for lifting the pawl 8 out of engagement with the ratchet wheel 12 and preventing it from driving the wheel 12 when its roll 10 engages the lifting surface 53. The lifting surface 53 is limited on 35 one side by a rest which accommodates the roll 10 when the stop nose 52 of the cam plate sector 50 engages the bolt 7 of the feed arm 5 in response to the action of the spring 51, as indicated in Fig. 1.

40 During the working stroke of the feed arm 5 the latter is followed by the cam plate sector 50 with the segment 49 owing to the action of the spring 51. The pawl roll 10 lies then in its rest which is so deep that the tooth of the pawl 8 engages the toothing of the ratchet wheel 12 and thus starts the motion of the latter as well as of the entire sheet feeding gear. This intermittent sheet feed is continued until the foremost or top sheet presses back the feeler spring 33, so that 45 the nozzle 39 is closed and the pump, by means of the conduit 38, 31, 41, causes a rarefaction of air in the cylinder 42, which brings about the displacement of the piston 43 towards the right, as indicated in Fig. 1, for pressing the pawl 47 by 50 means of the piston rod 45 into the toothing of the segment 49. The cam plate sector 50 is thus locked and cannot follow the feed arm 5 while the roll 10 is forced to enter the lifting path 53 and thus become disengaged from the toothing 55 of the ratchet wheel 12.

The suction control is regulated in known manner from the shaft 2 by means of a control valve or the like (not shown).

60 The separation of the sheets by the suction wheels or suction roller is carried out so that immediately after the rear end of the aspirated sheet has passed the suction wheels the next sheet is aspirated and drawn off from the pile. The suction control need be interrupted only for 65 a short time at each operation cycle of the ratchet gear to permit the feeler spring to swing back from the nozzle if pressure on the spring has ceased owing to the removal of the sheets and the reduction of the pile. Therefore, at each 70 operation cycle of the ratchet gear a control

valve, not shown, or other suitable means driven from the shaft 2 interrupts the connection between the nozzle and pump and establishes instant communication with the outer air.

By means of the set screw 27 the distance of 5 the suction wheels 21 from the surface of the pile can be adjusted according to the nature of the paper worked. It is advisable when changing the distance between the suction wheels and the surface of the pile to vary also the position 10 of the feeler spring 33 relative to the surface of the pile so that when the suction roller or wheels are only slightly removed from the surface of the pile, the projection of the point of the feeler spring relative to the support of the pile will be 15 correspondingly reduced. It will be noted, from Fig. 1, that the foremost sheet is lifted clear of the spring 33 before it is fed forward by the roll 21.

Fig. 2 shows a device for automatically regulating the position of the feeler spring relative to the support of the sheets in dependence upon the adjustment of the suction wheels relative to the surface or support of the sheets. The nozzle tube 37 is articulated to two parallel arms 55 25 which in turn are articulated to an arm 56 secured to the frame rod 54. The upper arm 55 is rigidly connected with an arm 57 whose free end is articulated by a link 58 to the carrying arm 24 of the suction wheels, so that when the spacing 30 of the suction wheels 21 relative to the support 18 is altered by the set screw 27, the parallel arms 55 will be swung down about their hinge bolts on the arm 56, owing to the lever connection 58, 57, and thus the nozzle tube 37 with the feeler spring 35 33 is moved up or down.

I claim:

1. A device for regulating the feed of an adjusted pile to sheet separating means, in which the foremost sheet of the pile, by striking a 40 feeler and closing a nozzle, automatically starts or stops the ratchet gear effecting the feed of the pile, particularly in sheet separation by means of suction rollers, suction wheels, or the like, and in which a feeler projecting from below into 45 the conveying path of the pile and held in control position is moved by the contact of the sheet with a control suction nozzle forming part of the regulating device in such a way that, owing to the suction pressure of the nozzle, it will close 50 the suction conduit thereof and a snuffle piston provided in the suction conduit and a ratchet pawl connected therewith will carry out a motion which serves for only temporarily stopping 55 the ratchet gear of the pile during the working stroke, an air control member disposed in the suction conduit being controlled so that it will temporarily connect the suction conduit with the outer air at each operation cycle of the ratchet gear and thus bring about the disengagement of 60 the feeler from the suction nozzle.

2. A device according to claim 1, in which the position of the feeler relative to the support of the pile is regulatable in dependence upon the distance of the suction roller or wheels from the 65 pile support.

3. In a feed regulating device, a crank disk, a ratchet wheel mounted for rotation, an arm oscillatably mounted concentric to the ratchet wheel, a rod connecting said disk and arm, to 70 oscillate the arm as the disk rotates, a pawl carried by said arm to engage the ratchet wheel, an endless belt driven from said ratchet wheel and adapted to support a series of sheets in overlapping relation, a plate extending forwardly 75

from the belt and over which said sheets are fed by the movement of the belt, a revolving suction drum underneath which said sheets successively pass, a cam member mounted concentrically of the ratchet wheel and having stop engagement with said arm upon movement of the cam member in the direction of forward movement of the ratchet wheel, a spring normally holding the cam member in engagement with said arm, a roller 5 on the free end of said pawl and located in the plane of the cam member, said cam member having a cam surface arranged to engage the roller and lift the pawl upon separation of said cam member and arm, a ratchet segment on said cam member, a pawl adapted to engage said ratchet segment and hold the cam member from movement under the influence of its spring, and means including a feeler engaged by the foremost sheet to effect movement of the last mentioned pawl into and out of engagement with the ratchet segment.

4. In a feed regulating device, a crank disk, a ratchet wheel mounted for rotation, an arm oscillatably mounted concentric to the ratchet wheel, a rod connecting said disk and arm to oscillate the arm as the disk rotates, a pawl carried by said arm to engage the ratchet wheel, an endless belt driven from said ratchet wheel and adapted to support a series of sheets in overlapping relation, a plate extending forwardly from the belt and over which said sheets are fed by the movement of the belt, a revolving suction drum underneath which said sheets successively pass, means to move said pawl to a position of disengagement from said ratchet wheel, means including a feeler engaged by the foremost sheet to effect action of the last mentioned means, means to support the suction drum for movement towards and from the plate, and means to hold the drum in adjusted position.

5. In a feed regulating device, a crank disk, a ratchet wheel mounted for rotation, an arm oscillatably mounted concentric to the ratchet wheel, a rod connecting said disk and arm to oscillate the arm as the disk rotates, a pawl carried by said arm to engage the ratchet wheel, an endless belt driven from said ratchet wheel and adapted to support a series of sheets in overlapping relation, a plate extending forwardly from the belt and over which said sheets are fed by the movement of the belt, a revolving suction drum underneath which said sheets successively pass, a cam member mounted concentrically of the ratchet wheel and having stop engagement with said arm upon movement of the cam member in the direction of forward movement of the ratchet wheel, a spring normally holding the cam member in engagement with said arm, a roller 45 on the free end of said pawl and located in the plane of the cam member, said cam member having a cam surface arranged to engage the roller and lift the pawl upon separation of said cam member and arm, a ratchet segment on said cam member, a pawl adapted to engage said ratchet segment and hold the cam member from movement under the influence of its spring, means including a feeler engaged by the foremost sheet to effect movement of the last mentioned pawl into and out of engagement with the ratchet segment, means to support the suction drum for movement towards and from the plate, means to hold the drum in adjusted position, means to support said feeler for movement toward and from the forward edge of said plate, and a linkage connecting the feeler provided means and the suction drum support to move the feeler provided means as the drum support is moved.

tioned pawl into and out of engagement with the ratchet segment, means to support the suction drum for movement toward and from the plate, and means to hold the drum in adjusted position.

6. In a feed regulating device, a crank disk, a ratchet wheel mounted for rotation, an arm oscillatably mounted concentric to the ratchet wheel, a rod connecting said disk and arm to oscillate the arm as the disk rotates, a pawl carried by said arm to engage the ratchet wheel, an endless belt driven from said ratchet wheel and adapted to support a series of sheets in overlapping relation, a plate extending forwardly from the belt and over which said sheets are fed by the movement of the belt, a revolving suction drum underneath which said sheets successively pass, means to move said pawl to a position of disengagement from said ratchet wheel, means including a feeler engaged by the foremost sheet to effect action of the last mentioned means, means to support the suction drum for movement toward and from the plate, means to hold the drum in adjusted position, means to support said feeler for movement toward and from the forward edge of said plate, and a linkage connecting the feeler provided means and the suction drum support to move the feeler provided means as the drum support is moved.

7. In a feed regulating device, a crank disk, a ratchet wheel mounted for rotation, an arm oscillatably mounted concentric to the ratchet wheel, a rod connecting said disk and arm to oscillate the arm as the disk rotates, a pawl carried by said arm to engage the ratchet wheel, an endless belt driven from said ratchet wheel and adapted to support a series of sheets in overlapping relation, a plate extending forwardly from the belt and over which said sheets are fed by the movement of the belt, a revolving suction drum underneath which said sheets successively pass, a cam member mounted concentrically of the ratchet wheel and having stop engagement with said arm upon movement of the cam member in the direction of forward movement of the ratchet wheel, a spring normally holding the cam member in engagement with said arm, a roller 45 on the free end of said pawl and located in the plane of the cam member, said cam member having a cam surface arranged to engage the roller and lift the pawl upon separation of said cam member and arm, a ratchet segment on said cam member, a pawl adapted to engage said ratchet segment and hold the cam member from movement under the influence of its spring, means including a feeler engaged by the foremost sheet to effect movement of the last mentioned pawl into and out of engagement with the ratchet segment, means to support the suction drum for movement toward and from the plate, means to hold the drum in adjusted position, means to support said feeler for movement toward and from the forward edge of said plate, and a linkage connecting the feeler provided means and the suction drum support to move the feeler provided means as the drum support is moved.
